ALFRED WINKLER AND MAX DUNNEBIER, OF NEUWIED-ON-THE-BHINE, GERMANY

BLANK FEEDING AND FOLDING APPARATUS

Application filed September 22, 1930, Serial No. 483,523, and in Germany September 28, 1929.

This invention relates to envelope machines, and more particularly to a blank folding and feeding mechanism therefor, wherein the bottom sheet of a stack of blanks is successively fed by rollers revolving against each other and adapted for engaging the blank to draw it into the machine with a single fold.

In feeding apparatus of this character the bottom blanks of the stack sag downward into the space above the point of contact of the rollers; the tendency to sag increasing proportionately to the thinness of the paper stock of which the blanks are formed, so that frequently two or more blanks are drawn into the machine at one time.

It is the principal object of this invention to provide apparatus of the character wherein sagging of the blanks is avoided and positive feed of only one blank at a time assured.

In accomplishing these and other objects of the invention, we have provided improved details of structure, the preferred forms of which are illustrated in the accompanying drawings, wherein:

Fig. 1 is a cross sectional view through blank feeding and folding apparatus equipped with our invention.

Fig. 2 is a plan view of the blank feeding rollers, illustrating a stack of blanks supported thereabove.

Referring more in detail to the drawings:

1 designates a preferably inclined plate for supporting a stack of blanks 2 which are positioned thereon by posts 3 engaging the sides of the stack. Formed in the plate is a rectangular opening 4 through which the blanks are successively drawn for delivery into the machine. Rotatably mounted in the frame 5 of the machine and positioned in the opening 4 is an indrawing roller 6 adapted for withdrawing the bottom blank from the stack, and cooperating therewith is a counter roller 7. The peripheral surfaces of the rollers thus described are spaced slightly from the top surface of the plate 1 and the outer sides of the rollers are received in concave recesses 8 and 9 formed in the edges of the plate opening, so that the effective width of the opening is reduced to a minimum dimension to in itself reduce tendency of the blanks to sag.

The indrawing roller 6 is preferably tubular and is provided with a plurality of openings 10 covering substantially one-quarter of its circumference and through which a vacuum is formed by a suitable pump (not shown).

The counter roller is retained in yielding contact with the indrawing roller and the rollers are operated by suitable gearing, so that upon each revolution of the indrawing roller the openings 10 come into receiving position with relation to the stack, and the vacuum drawn through the openings sucks the bottom blank downwardly in a trough-shape and into contact with the counter roller which cooperates therewith to fold the blank and feed it through spaced guides 11 and 12 into the forwarding rollers 13 and 14 of the machine.

In order that the blank may be readily withdrawn from the feeding rollers the indrawing roller is formed with a segmental recess 15 which freely receives the blank as soon as the forwarding rollers engage it, thereby releasing the blank for ready withdrawal into the machine.

As above stated the bottom blanks have a tendency to sag in the space 16 formed below the stack above the feeding rollers, and to obviate this objectional feature we provide the support and means for separating the blanks as now described.

Fixed at the lower ends of rods 17 and 18 at each side of the stack of blanks are conduits 19 and 20, respectively, leading from a compressed air supply (not shown), and which are provided at their free ends with nozzles 21 and 22 directed under the blanks and into the space 16 formed by the bottom of the blanks and the upper peripheral surface of the feeding rollers, whereby air under pressure may be discharged into the space for effecting support and retention of the bottom blanks during withdrawal of a blank by the rollers 6 and 7.

In instances where two or more sheets tend to stick together they are instantly separated by the air jets blowing against the edges of

the blanks as they are cupped downwardly across the paths of the jets which drive the bottom blanks downwardly and the upper blanks against the bottom of the stack to hold them back.

In order that the nozzles may be properly positioned so that the jets are directed in desirable relation with the edges of the blanks, the supports are adjustably mounted in brackets 23 and 24 by set screws as at 25, whereby the nozzles may be positioned relative to the feeding rollers and the bottom of the stack.

From the foregoing it is apparent that the blanks are in effect supported by the air jets but that the bottom blank may be readily separated from the stack by the jets to insure withdrawal of a single blank at a time. Also it is apparent that the air pressure within the space 16 fills out the blank after it has been cupped by the indrawing roller to materially assist in its orderly entrance between the rollers.

What we claim and desire to secure by Letters Patent is:

1. In combination, a blank feeding apparatus including a support for a stack of blanks, means for drawing blanks from the bottom of the stack, and means for directing an air jet across the bottom of the stack and adjacent the edges of a blank being drawn from the stack to assist in separation of the blank from the stack and to support the other blanks in the stack from sagging into the blank drawing means.

2. In combination with a blank feeding apparatus including a plate for supporting a stack of blanks and having a delivery opening therein, a pair of rollers associated with the plate and adapted for withdrawing blanks through the opening from the bottom of the stack, and means for directing an air jet between the stack and longitudinally of the rollers for preventing sagging of the blanks retained in the stack and to fill out a blank being removed against said rollers during operation of the said rollers.

3. In combination with blank feeding apparatus including a plate for supporting a stack of blanks and having a delivery opening therein, a pair of rollers associated with the plate and adapted for withdrawing blanks through the opening, and air discharge nozzles for directing an air jet between the stack and the rollers for preventing sagging of the blanks retained in the stack during operation of the said rollers.

4. In combination with blank feeding apparatus including a plate for supporting a stack of blanks and having a delivery opening therein, a pair of rollers associated with the plate and adapted for withdrawing blanks through the opening, nozzles for directing air jets between the stack and the rollers for preventing sagging of the blanks

retained in the stack during operation of said rollers, and means for adjusting the nozzles to position the air flow.

5. In combination with a blank feeding apparatus, a support for a stack of blanks, a pair of rotary members associated with the support to withdraw a blank from the stack and effect an initial fold therebetween, means for directing an air jet across the stack and between said rotary members to prevent sagging of the blanks in the stack and to fill out the blank being withdrawn against the rotary members to aid in its orderly entrance between said members to form the fold.

6. In combination with a blank feeding apparatus, a support for a stack of blanks, a pair of rollers for removing blanks from the stack and having longitudinal contact with each other to effect a fold of the blank being removed from the stack, and air discharge nozzles positioned in the space formed above the line of contact of said rollers for preventing sagging of the blanks in the stack during removal of the blank to fill out the blank being removed against said rollers.

In testimony whereof we affix our signatures.

ALFRED WINKLER.
MAX DUNNEBIER.
